UNITED STATES PATENT OFFICE

HARRY A. FOOHTHORAP, OF HARRISBURG, PENNSYLVANIA, ASSIGNOR TO ELLIOTT-FISHER COMPANY, OF NEW YORK, N. Y., A CORPORATION OF DELAWARE

TOLL POSTING MACHINE

Original application filed May 14, 1925, Serial No. 30,267. Divided and this application filed April 9, 1929. Serial No. 353,778.

My invention relates to improvements in toll posting machines of the flat platen typewriter class.

5 The object of the invention is to equip a machine of this character with means whereby successive toll slips may be quickly and accurately loaded upon the platen and as quickly ejected therefrom and stored in stack relation.

10 To the accomplishment of this general object and others subordinate thereto a preferred embodiment of the invention resides in the structure herein disclosed in conjunction with the accompanying drawings.

15 The present application is a division of my co-pending application Serial No. 30,267, filed May 14, 1925, now Patent No. 1,729,771, dated October 1, 1929, and to which attention is directed in connection with the present disclosure.

In the drawings:

Figure 1 is a longitudinal sectional view, partly in elevation, of a portion of a flat platen typewriter embodying my invention,

20 Figure 2 is a detail top plan view,

Figure 3 is a bottom plan view, and

25 Figure 4 is a fragmentary view similar to Figure 1 illustrating the operation of ejecting a toll slip from the machine.

30 The machine to which my invention is shown as applied is the Elliott-Fisher Billing Machine of commerce, which is so well known that it requires only the briefest explanation. In this machine the carriage 1 upon which the printing mechanism (not shown) is mounted, is movable in either a letter space or a line space direction over a depressible flat platen 2 mounted in a rectangular platen frame 3.

40 The carriage 1 is mounted, by roller bearings 4, for movement in a letter space direction upon a line space frame 5. The line space frame 5 is mounted, by means of roller bearings 6, for movement in a line space direction upon guides 7 surmounting the side members of the platen frame 3.

45 As will be understood the carriage 1 and line space frame 5 are actuated by suitable mechanisms for instance as disclosed in my co-pending application supra. The struc-

ture designated 8 is a motor return mechanism for the line space frame 5 which need merely be noted in passing.

55 The platen frame 3 is divided into front and rear sections by a transverse bar 9 surmounted by a work clamp 10. The work clamp 10 overlies the rear edge of the flat platen 2 which is mounted within the front section of the platen frame and provided with the usual rubber facing. The platen is intended as a support for the work sheet and is 60 depressible from the writing plane to the dropped or depressed position shown in Figure 4.

65 The front end of the platen is supported by a roller 11 carried by a roller bracket 12 pivoted on the front bar of the platen frame and urged toward the platen by a spring 13. This spring urged roller 11 is preferably mounted at the center of the front edge of 70 the platen as shown in Figure 3. At its rear end the platen 2 is supported from a rock shaft 14 extended across the frame 3 and having a pair of arms 15, the free ends of which extend between pins 16 carried by brackets 17, 75 depending from the platen and associated with a pendant yoke 18, connected as by a chain 19 with a pedal or other platen depressing device (not shown).

80 A pair of strong springs 20 are connected to the front bar of the frame and to headed screws 21 which serve both as securing devices for the arms 15 and as points of attachment for the springs 20 to the shaft 14. These springs tend to rock the shaft 14 for 85 the purpose of elevating the arms 15 and the platen 2 connected therewith. The platen is therefore strongly but yieldingly held in the writing plane with its rear edge against the underside of the clamp. The result of this 90 is that any work sheet imposed upon the platen and extended under the clamp will be securely held at its rear edge.

95 The present structure, however, is specifically designed for the posting of toll slips T (see Figure 2). These slips are of comparatively small size and of comparatively thin material. To facilitate the positioning of a slip on the platen an angular work guide 22 is secured to the platen in position to en- 100

gage and accurately locate the front edge and corners of the slip. It is also desired that when the slip has been posted it may be quickly ejected from its printing position on the platen and received by a storage hopper 23, carried by the platen frame 3, and held below the same. The transverse frame bar 9 is therefore formed with a throat 24 through which the bill may

5 be ejected by an ejector 25. The ejector 25 is in the form of a projection upstanding from an ejecting lever 26, pivoted at 27 to the under side of the platen and provided at its opposite end with a handle 28 extending 10 upwardly through a slot 29 in the platen, and bent over to an unobtrusive but readily accessible position.

The ejector lever 26 is urged rearwardly 20 by a spring 30 after the lever has been drawn forward and then released by the operator. The ejector 25, normally occupies a position in alignment with the rear edge of the guide so that it assists in locating the toll slip. It has been found, however, that the effective 25 ejection of the slip necessitates the rearward movement of the ejector beyond its normal position when snapped back upon its release. To attain this end and the subsequent return of the ejector to its proper

30 normal position, a rebound lever 31 is fulcrumed on the under side of the platen with one end urged by a spring 32 to oppose its opposite end to the movement of the ejector rearward of its normal position. Coacting 35 with the lever 31 is a stop 33 which normally arrests the lever 31 in position to accurately locate the ejector. The power of the spring 32, while less than that of the spring 30, is sufficient, under the normal tensions of these springs, to counteract the tendency of the spring 30 to move the ejector rearwardly beyond the position in which it serves as a guide for the toll sheet.

If, however, the ejector is drawn back by 45 the operator the increased tension of the spring 30 will retract the ejector with sufficient force to momentarily overcome the spring 32 when the ejector lever strikes the rebound lever, the impact serving to carry 50 the ejector rearwardly a sufficient distance and at a sufficient speed to cause the toll slip to be ejected from the platen and through the throat 24 to the hopper.

The operation of my invention is as follows:

When the posting of the slip has been completed, the platen is depressed against the resistance of its elevating springs 20 and the slip will be released from the clamp 10. 60 If now the operator retracts the ejector, its release will result in its swift rearward movement to strike the front edge of the toll slip a sharp blow and cause the slip to be discharged into the hopper 23. While 65 this action is taking place the operator places

the next toll slip on the guide 22 on the platen where it is held upon the elevation of the platen to normal position.

What I claim is:

1. In a machine of the class described, the combination with a flat platen, and printing mechanism thereover, of a storage receptacle located beyond one edge of the platen, and means for tilting the platen toward the receptacle to facilitate the transfer of a work element from the platen to the receptacle. 70 75

2. In a machine of the class described, the combination with a flat platen, and a printing mechanism thereover, of a storage receptacle located beyond one edge of the platen and below the plane thereof, a work clamp clamping the work to the platen at the edge thereof adjacent to the receptacle, and means for separating the clamp and the platen to facilitate the transfer of a work element from the platen to the receptacle. 80 85

3. In a machine of the class described, the combination with printing mechanism, of a flat platen tiltable to facilitate the discharge of a work element over one edge thereof, a work clamp cooperating with the discharge edge of the platen in the untilted position of said platen, and a storage receptacle located beyond the clamp to receive a work element discharged from said platen. 90 95

4. The combination with a platen, of an ejecting lever, an ejecting spring constantly urging said lever in one direction, a rebound lever and spring, respectively, acting against the ejecting lever in opposition to the ejecting spring and co-acting to counterbalance the urge of the ejecting spring in an intermediate position of the ejecting lever. 100

5. The combination with a platen, of an ejecting lever, a rebound device, and an ejecting spring for the lever, operative to move said lever beyond its normal position in opposition to the rebound device but having insufficient power to resist the return of the lever to its normal position by the rebound device. 105 110

6. The combination with a flat platen, and travelling printing mechanism thereover, of an ejecting device and a work clamp located at opposite edges of the printing area of the platen, a storage receptacle into which the work element is ejected from the platen, and means for tilting the platen to facilitate the ejection of the work. 115

7. The combination with a tiltable platen, of an ejector and a work clamp located at opposite edges thereof, and a storage receptacle to receive the work element ejected from the tilted platen after its release from the clamp by the tilting of the platen. 120 125

8. The combination with a stationary work clamp, a flat platen movable to and from the clamp, and a storage receptacle located beyond the clamp, of an ejector operative to 130

eject a work element from the platen and into the storage receptacle.

9. The combination with a depressible flat platen, platen depressing means connected to the rear end thereof, an ejector associated with the platen, a work clamp co-acting with the rear end of the platen, and a storage receptacle in rear of the work clamp.

10. In a machine of the class described, the combination with a depressible flat platen and printing mechanism thereover, of a work clamp cooperating with one edge of the platen, a storage receptacle located beyond the clamp to receive a work element transferred thereto from the depressed platen, and means for transferring the work element.

11. The combination with a flat platen and travelling printing mechanism, of an ejecting device and a work clamp located at opposite sides of the printing area of the platen respectively, and a storage receptacle located beyond the work clamp to receive a work element ejected past the clamp from the platen.

12. In a flat platen typewriter, the combination with a platen depressible from the writing plane, of a work clamp coacting with the platen at one side of the writing area thereof, an ejector located at the opposite side of the writing area of the platen, and a storage receptacle located beyond the work clamp to receive a work sheet ejected beyond the work clamp from the depressed platen.

13. In a flat platen typewriter, the combination with a platen frame having a transverse bar formed with an open throat, of a flat platen and a storage receptacle located at opposite sides of the bar, a work clamp carried by the bar and coacting with the platen, and an ejector associated with the platen to eject the work element therefrom.

14. In a flat platen typewriter the combination with travelling printing mechanism, of a platen element, a clamping element extended across and cooperating with the rear edge of the platen element, one of said elements being movable to effect its separation from the other element and permit a work sheet to be ejected under the clamp from the platen, and a storage receptacle located beyond the clamp.

In testimony whereof I affix my signature.

HARRY A. FOOTHORAP.
